Attorney.

UNITED STATES PATENT OFFICE.

LOUIS H. BLOOD, OF CINCINNATI, OHIO, ASSIGNOR TO THE OESTERLEIN MACHINE COMPANY, OF CINCINNATI, OHIO.

MILLING-MACHINE.

1,371,772.

Specification of Letters Patent. Patented Mar. 15, 1921.

Application filed December 6, 1919. Serial No. 343,023.

To all whom it may concern:

Be it known that I, Louis H. Blood, a citizen of the United States, residing in Cincinnati, Hamilton county, Ohio, have invented certain new and useful Improvements in Milling-Machines, of which the following is a specification.

This invention, relating to milling machines will be readily understood from the following description taken in connection with the accompanying drawings in which:—

Figure 1 is a side elevation of a milling machine, exemplifying my invention, portions of the vertically adjustable knee and the supporting standards therefor being broken away; and

Fig. 2, a plan of the machine, partly in horizontal section in the plane of lines 2 of Fig. 1.

In the drawing:

1, indicates the frame of the machine which is in the form of a hollow column open at its top:

2, the base-plate supporting the column, this base-plate extending well forward of the column:

3, the spindle of the machine, journaled in arms projecting as usual up from the top of the column:

4, a cone-pulley on the spindle:

5, a countershaft journaled in the base of the column:

6, a cone-pulley on the countershaft, corresponding with the cone-pulley on the spindle:

7, a belt engaging the two cone-pulleys, this belt being disposed within the hollow of the column and reaching the upper cone-pulley through the open top of the column:

8, a doorway in one side of the column:

9, a vertical dovetail on the front wall of the column:

10, a knee vertically adjustable upon this dovetail, the knee being of the usual form:

11, four hollow standards rising from the forward extension of the base-plate, under the knee, each standard bearing a nut in its top:

12, a screw engaging each of the nuts of the standards:

13, a spur-gear fast on each screw:

14, a vertical shaft journaled in the knee, central of the group of spur-gears 13:

15, a spur-gear fast on this shaft and in 55 mesh with gears 13:

16, a bevel-gear fast on this shaft:

17, a bevel pinion engaging this bevel gear: and

18, a horizontal shaft journaled in the 60 knee and having the bevel pinion 17 fast on its inner end, the outer end of this horizontal shaft being outside the knee and provided with a square or other facility for rotating the shaft.

Countershaft 5 is to be given rotation by any suitable means. The belt may be shifted on the cone-pulley, as usual. By turning horizontal shaft 18 the four screws may be rotated simultaneously, whereby the vertical position of the knee may be adjusted as desired. The provision of four elevating screws gives especially good support to the knee from the forward projection of the base-plate. The nuts in the tops of the 75 standards 11 are to be separably inserted in the standards and held against rotation by set screws, thus permitting the adjustment of the nuts with reference to each other so that all of the four screws partake equally 80 of duty in accurately sustaining the knee.

I claim:—

1. A milling machine comprising, a hollow column having an opening in one of its sides and having an open top, arms projecting upward from the column, a spindle joined in said arms, a cone-pulley on said spindle, a countershaft journaled in the base of the column, and a cone-pulley on said countershaft below the first mentioned cone-pulley, combined substantially as set forth.

2. A milling machine comprising, a column having a dovetail on its front, a base-plate supporting the column and projecting in front thereof, a knee fitted for vertical 95 adjustment on said dovetail, four hollow standards rising from the forward projection of the base-plate, nuts in the tops of said standards, screws engaging said nuts and having their tops journaled in the knee. 100 a shaft journaled vertically in the knee central of said four screws, spur-gears fast on the screws, a spur-gear fast on said vertical shaft and engaging the spur-gears on the screws, a bevel-gear fast on said vertical 105 shaft, a horizontal shaft journaled in the knee and adapted to be turned by hand, and a bevel pinion fast on said horizontal shaft

and engaging said bevel gear, combined substantially as set forth.

3. A milling machine comprising a column, a base plate supporting the column and projecting in front thereof, a knee fitted for vertical adjustment on the column, a plurality of hollow standards rising from the forward projection of the base plate, nuts in the tops of said standards, screws 5 engaging said nuts and having their tops journaled in the knee, a shaft journaled vertically in the knee centrally of said screws, spur gears fast on the screws, a spur gear fast on said vertical shaft and engaging the 10 spur gears on the screws, a bevel gear fast on said vertical shaft, a horizontal shaft journaled in the knee, and adapted to be turned by hand, and a bevel pinion fast on said horizontal shaft and engaging said bevel 15 gear, combined substantially as set forth.

4. A milling machine comprising a base plate, and a column rising from one end thereof, a knee fitted for vertical movement on the column, a plurality of standards ris- 20

ing from the base plate in front of said column, screws adjustable with respect to said standards and having their upper ends journaled in said knee, and operating means common to all of said screws for simultaneously adjusting the screws relatively to 25 their respective standards.

5. A milling machine comprising a base plate, and a column rising from one end thereof, a knee fitted for vertical movement on the column, a plurality of standards ris- 30 35 40 ing from the base plate in front of said column, screws adjustable with respect to said standards and having their upper ends journaled in said knee, each screw being individually adjustable with respect to its associated standard and operating means common to all of said screws for simultaneously adjusting all of them relatively to their respective standards.
